ROSE PLANT

Esther Gladys Fisher, Woburn, Mass., assignor to The Conard-Pyle Company, West Grove, Pa., a corporation of Pennsylvania

Application May 5, 1959, Serial No. 811,243

1 Claim. (Cl. 47—61)

The present invention relates to a new and distinct 15 variety of rose plant of the hybrid tea class, which was originated by me by crossing the variety Peace (Plant Patent No. 591) with the variety Orange Nassau (Plant Patent No. 350).

The primary objective of this breeding was to produce 20 a new rose variety which would combine the vigor, bloom form and other desirable characteristics of Peace with the copper-orange color tones of Orange Nassau.

As a result of this breeding, I have produced a new 25 rose variety which is distinctly different from both its parents, as well as all other varieties of its class of which I am aware, as evidenced by the following characteristics which are outstanding and which in combination are unique:

(1) The Rose Opal general color tonality which is 30 suffused with Empire Yellow around the margin of the flower with the center showing Aureolin 3;

(2) The glossy green foliage;

(3) The bushy well branched habit of growth;

(4) The graceful long pointed bud.

Asexual reproduction of my new variety at West Grove, Pennsylvania, shows that the aforementioned characteristics come true to form and are established and transmitted through succeeding propagations.

The accompanying drawing shows typical specimens of 40 the growth and flower of my new variety in different stages of development and as depicted in color as nearly true as it is reasonably possible to make the same in color illustration of this character.

The following is a detailed description of my new 45 variety with color terminology in accordance with the Horticultural Color Chart of the Royal Horticultural Society:

Type: Hardy; bush; outdoor; seedling; for garden decoration.

Class: Hybrid tea.

Breeding: Seedling.

Seed parent.—Peace.

Pollen parent.—Orange Nassau.

Propagation: It does hold its distinguishing characteristics through succeeding propagations by budding.

Flower

Locality where grown: West Grove, Pennsylvania.

Flowers borne: Singly, sometimes two, three or four to 60 stem; normal; medium stems.

Quantity of bloom: Free outdoors.

Continuity: Continuous.

Fragrance: Moderate; tea.

Bud:

Penduncle.—Medium; erect stiff; Lettuce Green 861/3 overlaid with Garnet Brown 00918/3; rough; numerous hairs; brown.

Before calyx breaks.—Size—Medium large. Form—70 long pointed with a conspicuous neck; with foliaceous appendages on the surface of the bud; with

2

slender bristle-like foliaceous parts extending beyond the tip of the bud equal to $\frac{1}{4}$ or more of its length.

As calyx breaks.—Color—Currant Red 821.

As first petal opens.—Size—medium large. Form—long pointed. Color: outside—a thin margin of Rose Madder 23/2 at outer edge of petal surrounding, over upper half of petal, Straw Yellow 604/2 and over lower half of petal, Chinese Yellow 606/1 at times overlaid with Saturn Red 13/2. Basal area Empire Yellow 603; inside—upper half petal Rose Opal 022/1 streaked with Empire Yellow 603 grading to Lemon Yellow 4 over lower half of petal occasionally tinted with Lemon Yellow 4/2.

Opening.—It does open up well.

Bloom:

Size when fully open.—Large, $4\frac{1}{4}$ inches to $4\frac{1}{2}$ inches.

Petalage.—Double; from 20 to 25 petals; arranged regularly.

Form.—High centered at first; becoming open cupped; petals remaining at first loosely rolled outward; becoming later at maturity loosely rolled outward.

Petals: Thick leathery; with inside satiny; outside shiny.

Shape.—Outer—obovate. Intermediate—obovate. Inner—obovate.

This description of a newly opened flower was made from a rose grown outdoors in October, 1958, at West Grove, Pennsylvania.

Color.—Outer petal: outside surface—a thin margin of Neyron Rose 623/2 surrounding Chrome Yellow 605/2 over upper half of the petal. Lower half of petal Mimosa Yellow 602/1; inside surface—Rose Opal 022/1 over upper $\frac{1}{3}$ of petal becoming streaked with Empire Yellow 603/1 over center $\frac{1}{3}$ grading to Aureolin 3/1 over basal $\frac{1}{3}$ of petal. Intermediate petal: outside surface—Chrome Yellow 605/2 margined with Neyron Rose 623/2 over upper half of petal grading to Mimosa Yellow intermediate between 602 and 602/1 over lower half of petal; inside surface—Rose Opal 022/1 grading to Claret Rose 021 lightly striped with Aureolin 3 which color covers the basal $\frac{1}{3}$ of the petal. Inner petal: outside surface—Chrome Yellow 605/1 over upper half of petal grading to Straw Yellow 604; inside surface—Scarlet intermediate between 19 and 19/1 over upper half of petal becoming washed with and grading into Aureolin 3.

This description was made from a rose that was open 55 for three days, outdoors in October 1958, at West Grove, Pennsylvania.

Color.—Outer petal: outside surface—Amber Yellow 505/2 grading to Mimosa Yellow 602/1; inside surface—Crimson 22/2 washed with 22/3 grading to Mimosa Yellow 602/1 shaded with Aureolin 3. Inner petal: outside surface—Amber Yellow 505/2 grading to Mimosa Yellow 602/1; inside surface—Spinel Red 0023 over upper half of petal becoming washed with and grading into Mimosa Yellow 602/1 shaded with Aureolin 3.

General color effect.—Newly opened flower—Rose Opal 022/1 suffused with Empire Yellow 603/1. Three days open—Crimson 22/2 suffused with Mimosa Yellow 602/1, with center of bloom Mimosa Yellow 602/1 shaded with Aureolin 3.
